WRISTWATCH COMMUNICATION TRANSMITTER

Jack C. Roberts, 23660 Pacific Coast Highway, Malibu,
Calif. 90265, and Charles J. Smith, 11459 Bellagio
Road, Bel Air, Calif. 94558

Filed Jan. 26, 1967, Ser. No. 5,572

Term of patent 14 years

(Cl. D26—14)

FIGURE 1 is a perspective view of a wristwatch communication transmitter, showing my new design;

FIGURE 2 is a top plan view thereof;

FIGURE 3 is a bottom plan view thereof;

FIGURE 4 is a side elevation view thereof as seen from one side;

FIGURE 5 is a side elevation view thereof as seen from the other side;

FIGURE 6 is a view similar to FIGURE 1 showing the antenna rotated to another position and extended; and

FIGURE 7 is a perspective view of a modified embodiment of the transmitter shown in FIG. 1, with the antenna in a retracted position.

The broken line showing of a wrist strap and watch dial face and hands in FIGURES 1, 6 and 7 is merely for illustrative purposes.

We claim:

The ornamental design for a wristwatch communication transmitter, substantially as shown and described.
